UNITED STATES PATENT OFFICE.

JAMES WINDRIDGE AND GEORGE S. WILCOX, OF MIDDLEFIELD, CONNECTICUT, ASSIGNEES
TO LYMAN GUN SIGHT CORPORATION, OF MIDDLEFIELD, CONNECTICUT, A CORPORATION
OF CONNECTICUT.

SIGHT FOR FIREARMS.

No. 872,706.

Specification of Letters Patent.

Patented Dec. 3, 1907.

Application filed January 16, 1907. Serial No. 352,626.

To all whom it may concern:

Be it known that we, JAMES WINDRIDGE and GEORGE S. WILCOX, citizens of the United States, and residents of Middlefield, 5 in the county of Middlesex and State of Connecticut, have invented certain new and useful Improvements in Sights for Firearms, of which the following is a full, clear, and exact specification.

10 Our invention relates to that class of sights for firearms known as leaf or notched sights, or that in which the line of aim is taken centrally through a notch or depression in a thin leaf or blade mounted vertically 15 on the arm between the front sight and position of the eye in firing. To define the central vertical longitudinal plane through the notch in such sights, and facilitate accurate 20 sighting, a vertical line graved on the front side of the leaf or blade has been employed, or a thin strip of ivory embedded therein in said position.

Our improvement has for its object and 25 contemplates the use of a line of light for this purpose, and the invention consists in the novel arrangement, combination and construction of parts whereby this end is attained, as hereinafter more fully described and claimed.

30 In the accompanying drawings forming a part of this specification, Figure 1 is a side elevation of a folding leaf sight embodying my improvements. Fig. 2 is a rear elevation of Fig. 1, showing the profile of the 35 sighting notch. Fig. 3 is an elevation similar to Fig. 2 showing the sight blades reversed to provide a sighting notch of different form. Fig. 4 is a vertical longitudinal cross section on the line XX of Fig. 3. Fig. 40 5 is a rear elevation of the folding leaf detached from the base and with the sight blades removed. Fig. 6 is a horizontal section through the base on the pivotal plane of the leaf, or line XX of Fig. 1. Figs. 7 and 8 45 are views of the sight blades removed from the leaf. Fig. 9 is a central cross section 50 through the base. Fig. 10 is a side elevation of the base.

Referring to the drawings A designates a 55 sight base of a common and well known form having beveled front and rear edges b adapted to be inserted in a transverse dovetailed notch on the upper side of the barrel of a firearm. The configuration of the upper surface of the base is such that a hinge ear d is provided at each end thereof, in the central

vertical plane between the beveled edges b. The perforations e through the ears are in alinement with each other and screw threaded to receive the screw studs f, which are inserted from the outer sides of the ears and 60 are provided with the reduced cylindrical portions g projecting inwardly from the ears or toward each other, as shown in Fig. 6. The said cylindrical portions g comprise the pivots upon which the folding leaf or sight carrying part is hinged. It is common in this 65 class of sights to mount a pair of leaves upon the same axis, in which case, as in the drawing, the main leaf H may be provided with a pair of eyes i fitting between the hinge ears 70 d, and the secondary leaf L formed with a single eye M fitted between those of the main leaf. It is to the main leaf H that my 75 improvements are shown to be applied, and which are described as follows. The leaf is formed with a horizontal groove R extending entirely across its rear face, of dovetailed cross section having the greater width at the bottom, or with the bevel of its sides overhanging the groove. At the central 80 part of the leaf is a space t, the depth of which is substantially coincident with the width of the groove. In the groove are fitted a pair of thin blades n, one on each end of the leaf and arranged with their inner ends 85 overlapping upon the space t. The ends of the blades are vertical or square with the groove R for a distance from their lower corners and above the said vertical parts they are cut back or away from the planes thereof 90 in such shape that when placed together they will form a sighting notch as r¹ in Fig. 2, and r² in Fig. 3. The configuration of the said notch may be triangular as shown in Fig. 2, or semicircular as in Fig. 3, or of any other 95 required form. Different shaped profiles may be formed at opposite ends of the blades as shown in the drawings, and the parts reversed in the groove R to provide two styles of notches, as fully illustrated in Figs. 2 100 and 3.

The blades are secured in the groove R by means of binding screws i¹ screwed into screw threaded perforations i² in the leaf on the lower side of the groove, in such position 105 that the heads of the screws will impinge slightly upon the lower edges of the blades n to clamp the blades in their seats. Suitable countersinks i³ are formed around the perforations i² to receive the heads of the screws 110

and permit the latter to be screwed down below the surface of the leaf to the extent necessary to insure contact with the blades when the latter are in any degree below said surface of the leaf.

In operation the blades *n* are adjusted in the groove *R* of the leaf with the vertical parts of their inner ends nearly abutting together at the central cross plane of the leaf, 10 which is the vertical plane of the axis of the gun barrel. The resulting space between the ends of the blade comprises an exceedingly attenuated vertical slot *e*¹, placed exactly beneath the lowest or central part of the 15 sighting notch, and in continuation therewith. To the eye, in aiming this slot presents the appearance of a thin line of light which is of much less width than a clearly visible line cut or formed by graving, and 20 much brighter than a bar of ivory or other white substance inlaid in the leaf. It serves to define the vertical sighting plane on the field of vision with great clearness and the utmost degree of precision.

25 The actual width of the slot *e*¹ is in practice very minute, and is necessarily exaggerated in the drawing, as it is in fact less than the width of an ink line. The smallest space possible to provide, which is with the ends of 30 the blades set as closely together as they can be placed without being in contact, exhibits a distinct line of light to the eye, in aiming, and is of sufficient width to be clearly distinguished. It is so minute that it is most ad- 35 vantageously made or produced by using separate or individual parts which may be finely adjusted relatively to each other.

The sight leaf *H* is adapted to be folded forward and down to the horizontal position 40 to permit the use of the secondary sight leaf *L* which may then be raised to place. The leaf *L* folds correspondingly down and rear- 45 ward while the main leaf is elevated, as shown in the drawings. But these features are wholly independent of my invention, which relates to the combination with the sighting notch of a sight, of a vertical line of light below the notch in the central vertical plane thereof. It is equally applicable 50 to both folding and nonfolding sight leaves or those of any other class.

We claim as our invention:

1. A sight for firearms having an attenuated slot permitting the passage of a mere line of light, said slot being formed between the edges of two separate independent members said edges being nearly in contact.
2. A sight for firearms comprising a leaf or blade divided into separate parts having a space between their edges that forms an attenuated slot permitting the passage of a mere line of light in the vertical sighting plane said edges being nearly in contact.

3. A sight for firearms comprising a leaf or blade having a sighting notch and an attenuated slot below and central of the notch permitting the passage of a mere line of light in the vertical sighting plane said blade consisting of two separate parts between the edges of which said notch and slot are formed said slot being between portions of the edges that are nearly in contact. 65

4. In a sight for firearms the combination of a leaf and a pair of blades secured thereon with their edges separated to provide an intervening attenuated slot in the vertical sighting plane. 70

5. In a sight for firearms the combination of a leaf and a pair of blades secured on the leaf with their edges separated to provide an intervening sighting notch and an attenuated slot below and in continuation therewith in the vertical sighting plane. 80

6. In a sight for firearms the combination of a leaf having a horizontal groove and a central sighting space, a pair of blades movably seated in the groove with their ends overlapping upon the sighting space of the leaf and in juxtaposition, and means for clamping the blades in their seats, the configuration of the said ends of the blades comprising a sighting notch and a vertical attenuated slot in continuation thereof in the vertical sighting plane. 85

7. In a sight for firearms the combination of the leaf having the horizontal dovetailed groove and central sighting space, the blades seated in the groove and overlapping upon the sighting space, and the set screws, screwed into the leaf with their heads impinging upon the blades to clamp them in place, said blades forming an attenuated slot between them in the vertical sighting plane, and a sighting notch above the slot, substantially as specified. 90

8. A sight for firearms having two separate adjustable blades whose edges are separated by a space to form an attenuated slot permitting the passage of a mere line of light said edges being nearly in contact. 95

9. In a sight for firearms, the combination of a leaf having a horizontal groove, a pair of blades movably seated in the grooves in line with each other with their adjacent edges separated by a space to form an attenuated slot adapted to develop a line of light. 100

Signed by us at Middlefield, Connecticut this 28th day of December 1906.
